P. NICHOLSON.
SPHYGMOMANOMETER.
APPLICATION FILED NOV. 8, 1913.

1,094,464.

Patented Apr. 28, 1914.

UNITED STATES PATENT OFFICE.

PERCIVAL NICHOLSON, OF ARDMORE, PENNSYLVANIA.

SPHYGMOMANOMETER.

1,094,464.

Specification of Letters Patent. Patented Apr. 28, 1914.

Application filed November 8, 1913. Serial No. 799,849.

To all whom it may concern:

Be it known that I, PERCIVAL NICHOLSON, a citizen of the United States, residing at Ardmore, in the county of Montgomery and 5 State of Pennsylvania, have invented certain Improvements in Sphygmomanometers, of which the following is a specification.

My invention is a sphygmomanometer provided with a tube, a valve mechanism connected therewith, and a second tube connected in detachable relation to said first tube through said valve mechanism, by peculiar supporting means comprising, in its preferred form, a clip fixed to the valve and 15 adapted to be turned therewith.

The primary object of my improvements is to provide a simple, compact and efficient device, movable with the opening and closing of the valve into its operative and inoperative positions, for supporting the detachable tube in its operative position, while permitting the ready connection of said tube when the valve is open and disconnection of said tube prior to closing said valve.

It is a further object to provide an extended supporting device for the detachable tube and for the folding of said device within the limits of the case of the apparatus when the latter is not in use.

In the accompanying drawings, Figure 1 is a front elevation of a sphygmomanometer embodying my improvements in operative relation; Fig. 2 is a broken part sectional side elevation of the same; Fig. 3 is a sectional view taken on the line 3-3 of Fig. 2; and Fig. 4 is a broken elevation representing details of the construction in the inoperative relation.

The apparatus, as illustrated in the drawings, comprises the case 1 having the hinged lid 2, within which is fixed the cistern 3, the glass tube 4 connected with the bottom of the cistern, the valve casing 5 having the fenestrated socket 6 for holding the top of 45 the tube, the fenestrated valve 7 adapted to be turned in the casing by the handle 8, the resilient clip 9 fixed by the shank 10 to the rear end of the rotary valve, and the glass tube 11 adapted to pass through the clip 9, 50 casing 5 and valve 7, in the open position of the latter, into the top of the tube 4, the latter having the conical seat 4' for receiving the reversely tapered end 11' of the tube 11.

In the operative relation of the parts, as illustrated in Fig. 1, pressure is communi-

cated to the surface of mercury in the cistern 3 by means of the pneumatic bulb 12 connected with the cistern through the tube 13 and fixture 14 which is fixed to the lid (a like pressure being communicated from the fixture through the tube 15 to the cuff 16), the mercury rises in the tubes 4 and 11 with the pressure, and the height of the column in the tube or tubes is read by the scale comprising the section 16 held adjacent to the tube 4 and the section 17 connected to the section 16 by the hinge 18 and held thereby adjacent to the tube 11.

When the apparatus is not in use, the tubes 13 and 15 are detached from the fixture 14; the tube 11 is withdrawn from its frictional engagement in the clip 9, valve 7, and socket 4' and placed in its tubular holder 19 fixed within the lid 2; the scale section 17 is turned down on its hinge 18 against the section 16, and the handle 8 is turned from the position shown in Fig. 1 to that of Fig. 4 so as to effect the closure of the valve 7 and permit the closure of the lid 2 by bringing both the handle 8 and the clip 9 with its shank 10 at right angles to the tube 4 and within the limits of the lid.

It will be understood that as the lid cannot be closed until the valve is closed, because of the projection of the handle 8 and clip 9 beyond the lid in the open position of the valve, mercury cannot escape from the tube 4 when the lid is closed, and in the closed or other position of the lid mercury is prevented from escaping from the cistern 3 to the fixture 14 by any suitable means, as the capillary tube 20 extending downwardly in the cistern from the top thereof and having its reduced end above the mercury in all positions of the cistern. The supporting shank 10 is adapted to serve as a handle for turning the valve and as a means for preventing the closure of the lid in the open position of the valve.

Having described my invention, I claim:

1. In a sphygmomanometer, a tube, a valve casing fixed to an end of said tube, a valve movable in said casing whereby said tube is opened and closed, a second tube connected with said tube first named through said valve, and means fixed to and movable with said valve whereby said second tube is supported.

2. In a sphygmomanometer, a tube, mechanism fixed to the end of said tube, a valve movable under control of said mechanism

whereby said tube is opened and closed, a supporting device comprising a clip fixed to said valve, and a second tube adapted to be held by said clip and valve in registration with said tube first named.

3. In a sphygmomanometer, a case having a lid, a valve casing fixed to the inner face of said lid, a tube fixed to the inner face of said lid with its end fixed to said casing, a valve adapted to turn in said casing to open and close said tube, a detachable tube adapted to pass through said valve in the open position thereof into registration with said tube first named, and a device fixed to said valve and adapted for supporting said detachable tube, said device extending beyond

said lid in the open position of said valve and lying within the limits of said lid in the closed position of said valve.

4. In a sphygmomanometer, a tube, a valve mechanism comprising a valve adapted for opening and closing said tube, a second tube connected with said first tube through said valve, and means for supporting said second tube.

In testimony whereof I have hereunto set my hand this 7th day of Nov., 1918, in the presence of the subscribing witnesses.

PERCIVAL NICHOLSON.
